SHOE HEEL

Michael J. Goldberg, Pittsburgh, Pa.

Application June 16, 1943, Serial No. 491,269

1 Claim. (Cl. 36—36)

This invention relates to improvements in shoe heels, and while primarily designed and intended for rubber heels, it will be obvious that the invention may be successfully embodied in heels constructed of leather, plastic, composition, or any other suitable material.

Important objects and advantages of the invention are to provide a shoe heel of the character described, which embodies a removable and replaceable heel section at the part of the heel usually most subject to wear whereby the wearing life of the heel is doubled or at least appreciably prolonged, which may be embodied in the shoe structure by the manufacturer and replacement of the removable heel section made readily by the user himself when required, which will renovate run-down heels on otherwise good heel structures, which eliminates the distortion and discomfort of shoes and feet caused by walking on run-down heels, which is simple in its construction and arrangement, highly efficient in its use, and comparatively economical in its manufacture, attachment, and use.

With the foregoing and other objects in view which will appear as the description proceeds, the invention resides in the novel construction, combination and arrangement of parts herein specifically described and illustrated in the accompanying drawing, but it is to be understood that the latter is merely illustrative of an embodiment of the invention, and that changes in the form, proportions, and details of construction may be resorted to that come within the scope of the claim hereunto appended.

In the drawing wherein like numerals of reference designate corresponding parts throughout the several views:

Figure 1 is a bottom plan view of a shoe heel constructed in accordance with the invention.

Figure 2 is a side elevational view thereof with the replaceable section removed therefrom.

Figure 3 is a rear view of the improved heel, partly in cross section, and illustrating its connection with the associated heel base.

Figure 4 is a perspective view of the replaceable heel section.

Figure 5 is a plan view of a reinforcing member embodied in the present invention.

Referring in detail to the drawing 1 denotes the main body of a shoe heel, which is generally of the conventional construction universally employed in the manufacture of rubber shoe heels, excepting that same is constructed with a comparatively large indentation 2. The latter is disposed at the rear outer side of the main body 1,

which location is the part of the heel that is run-down from wear in fully ninety percent of run-down heel conditions.

The indentation 2 has a straight side wall 3 and a straight end wall 4, which latter is disposed at right angles with respect to said side wall 3. The side wall 3 extends at an angle of approximately sixty degrees, relatively to the longitudinal center of the main body 1, and has its outer or rearward end preferably disposed slightly beyond or inward of said longitudinal center.

The top edge margins of the side and end walls 3 and 4 are recessed to provide communicating grooves, respectively indicated at 5 and 6, when the main body 1 is secured to and against the usual heel base 7 of a shoe in the manner well known in the art, whereby the bottom of the heel base 7 provides the top walls of said grooves 5 and 6.

A replaceable heel section 8 is mounted in the indentation 2 of the heel main body 1 and is complementary to the latter in forming the full and complete heel structure.

The heel section 8 has a straight inner side wall 9 and a straight forward end wall 10 which abut against respective side and end walls 3 and 4 of the indentation 2. The top of the walls 9 and 10 are provided with respective connecting flanges 11 and 12, which engage in respective grooves 5 and 6 formed in the walls of the indentation 2.

As the heel section 8 is complementary to the main body 1, the outer peripheral wall of the former is suitably curved to form the proper heel curvature between the outer ends of the indentation walls 3 and 4, as clearly illustrated in Figures 1 and 3.

The heel section 8 is secured in position in the heel structure and against the bottom of the heel base 7 by means of a screw 13, which extends through a countersunk aperture 14 provided therefor in the heel section 8 and engages in the heel base 7.

If the improved heel is embodied in the shoe structure by the manufacturer, a nut 15 for the screw 13 is preferably embedded in the heel base 7 to provide a more substantial and definite attaching engagement for said screw 13. To further enhance the stability of the stated screw attachment, a foraminous reinforcing member 16 may be molded into the heel section 8. The screw 13 passes through and may have threaded engagement with the latter.

It will be noted that the engagement of the

section flanges 11 and 12 in respective body grooves 5 and 6 will provide holding attaching means for the heel section 8 extending throughout the lengths of the embodied side and end walls 9 and 10. Such engagement of the flanges, in conjunction with the engaged screw 13 will effectively secure the heel section 8 against movement in the heel structure. It is, of course, apparent that cement also may be employed in connection with the above described attaching elements, or that nails, or other suitable attaching means may be used instead of the screw 13 without departing from the spirit or sacrificing any advantages of the invention.

In employing the improved heel, it is, of course, necessary to provide conversely arranged indentations 2 and heel sections 8 to suit same for use on both right and left shoes of a pair of shoes.

If the improved heel structure is embodied in the shoe by the manufacturer, a pair of extra heels sections 8 are preferably included in the sale of the shoes to replace the pair on the shoes when such replaced pair become run-down from wear. Such replacement may be readily effected by even an unskilled person, as it only involves removing the screws and worn sections and replacing the latter and said screws. No trimming or fitting is required, as the extra sections furnished by the manufacturer conform exactly to the contour of the heels in connection with which they are supplied.

In repair work by a shoemaker, the latter simply replaces only the heels sections 8 instead of

the entire heels, assuming, of course, that the heels originally or previously were provided with the improved heels. Further, the heels sections 8 may be procured separately and mounted or attached by the user himself.

The present invention provides a most efficient device of its kind, which will obviously conserve the use of rubber, which may be economically manufactured, and which may be successfully employed in the manner and for the purpose herein set forth.

What I claim is:

A shoe heel structure comprising in combination, a heel base, a threaded nut embedded in said base, a rubber heel body secured to said base, said body being provided with an indentation having a straight side wall and a straight end wall which latter extends at right angles with respect to said side wall, the top edge margins of said side and end walls being recessed to provide a connecting groove in conjunction with the adjacent face of said base, a rubber heel section mounted in said indentation and being shaped to conform to the contour of said indentation, said section including projecting flanges engaging in said connecting groove, a foraminous reinforcing member embedded in said section, and a screw extending through said section and through said member and engaging in said nut for removably securing said section with said body and to said base.

MICHAEL J. GOLDBERG.
